His Attorney

UNITED STATES PATENT OFFICE

HENRY S. YOUNG, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA

ELECTRICAL CONTROLLING APPARATUS

Original application filed May 7, 1927, Serial No. 189,614. Patent No. 1,744,821, dated January 28, 1930.
Divided and this application filed November 9, 1929. Serial No. 405,953.

My invention relates to electrical controlling apparatus, and particularly to apparatus for controlling an electric motor such as a railway switch operating motor or the like, 5 from a remote point.

The present application is a division of my copending application, Serial No. 189,614, filed May 7, 1927, for electrical controlling apparatus, which has matured into Patent 10 No. 1,744,821, January 28, 1930.

I will describe one form of apparatus embodying my invention, and will then point out the novel features thereof in claims.

The accompanying drawing is a diagrammatic view illustrating one form of apparatus embodying my invention.

Referring to the drawing, my invention is shown as comprising railway traffic controlling devices, here shown as two switches 20 of a crossover designated respectively A and A¹ which are each provided with an operating motor designated by the reference characters M and M¹, respectively. The switch A actuates a circuit controller P comprising a contact 38-39 which is closed at all times except when the switch occupies its full reverse position. The circuit controller P also comprises a contact 40-41 which is closed when the switch occupies its 25 normal position and a contact 40-42 which is closed at all other times. In similar manner a circuit controller P¹ controlled by switch A¹ comprises a contact 46-47 closed at all times except when the switch A occupies its full normal position. The circuit controller P¹ also comprises a contact 43-44 which is closed when the switch A¹ occupies its reverse position and a contact 43-45 which is closed at all other times.

40 The motor M is controlled by a manually operable lever L which may be one of a number of such levers located at a point remote from the switch, such, for example, as in an interlocking cabin. As here shown, the lever 45 L is capable of assuming four positions indicated by dotted lines on the drawing, and designated by the reference characters N, B, D and R. The lever L controls two NB contacts which are closed for all positions of the lever between N and B, and two RD contacts

which are closed for all lever positions between R and D.

As shown in the drawing the lever L occupies its normal position N, and switches A and A¹ are both normal. If the operator 55 wishes to reverse the switches A and A¹, he moves the lever L toward its reverse position, to close the RD contacts on the lever. Current then flows from terminal X of a source of energy not shown in the drawing, 60 through an RD contact on lever L, conductor 11, contact 43-45 of circuit controller P¹, asymmetric unit 48, field 2 of motor M¹, asymmetric unit 50, wire 52, armature 1 of motor M¹, conductor 10 and a second RD 65 contact on lever L and back to terminal Y of the same source. Motor M¹ is, therefore, operated to move the switch A¹ to its reverse position. When the switch finally attains this position, contact 43-45 opens and contact 43-44 becomes closed. This opening of contact 43-45 discontinues the supply of energy to motor M¹ and the closing of contact 43-44 completes a circuit over which current is supplied to motor M, from terminal X, 70 through an RD contact on the lever L, conductor 11, contact 43-44 of circuit controller P¹, wire 53, contact 38-39 of circuit controller P, asymmetric unit 6, field 2 of motor M, asymmetric unit 8, wire 14, armature 1 75 of motor M, conductor 10, and an RD contact on the lever L, to terminal Y. Current supplied to the motor M over the circuit just traced causes the motor to move switch A to its reverse position, thereby opening contact 80 38-39 and discontinuing the supply of energy to the motor M.

In order to restore the switches A and A¹ to their normal positions, lever L is returned 85 toward its N position. When the NB contacts on the lever are closed current flows from terminal X over an NB contact on the lever, conductor 10, armature 1 of motor M, wire 14, asymmetric unit 7, field 2 of motor M, asymmetric unit 9, contact 40-42 of circuit controller P, wire 54, conductor 11, and an NB contact on lever L to the terminal Y. When the motor M has returned switch A to its normal position, the closing of contact 40-41 90 of circuit controller P completes a 95 100

circuit over which current flows from terminal X over an NB contact on lever L, conductor 10, armature 1 of motor M¹, wire 52, asymmetric unit 49, field 2 of motor M¹, asymmetric unit 51, contact 46—47 of circuit controller P¹, wire 55, contact 40—41 of circuit controller P, wire 54, conductor 11, and an NB contact on lever L to terminal Y. It will therefore, be observed that when the lever L is moved from one extreme position to the other, the motors M and M¹ are successively operated to reverse the corresponding switches. That is to say, in moving from normal to reverse, the motor M¹ is first connected with the source and when this motor has moved its switch to the full reverse position, the motor M is connected with the source. Similarly, in switch movements from reverse to normal, the motor M is first connected with the source, and motor M¹ is not supplied with energy until switch A has been restored to its full normal position.

It should be understood, of course, that the lever L may be provided with locking apparatus similar to that shown in my co-pending application hereinbefore referred to, and that an indication relay may be controlled by pole-changers associated with the switches A and A¹ in accordance with the usual and standard practice. These parts have been omitted from the present drawing in order to simplify the disclosure.

Although I have herein shown and described only one form of electrical controlling apparatus embodying my invention, it is understood that various changes and modifications may be made therein within the scope of the appended claims without departing from the spirit and scope of my invention.

Having thus described my invention, what I claim is:

1. In combination, a first railway switch, a first motor for operating the first switch and including two windings, a second motor for operating the second switch and comprising two windings, normal and reverse contacts controlled by each said switch, a manually operable lever having normal and reverse contacts, eight asymmetric units; a first circuit including a reverse contact of the lever, a normal contact of the second switch, a first and a second asymmetric unit, and the two windings of the second motor in series, a second circuit including a reverse contact of the lever, a reverse contact of the second switch, a normal contact of the first switch, a third and a fourth asymmetric unit, and the two windings of the first motor in series; a third circuit including a normal contact of the lever, the two windings of the first motor in series, a fifth and a sixth asymmetric units, and a reverse contact of the first switch; and a fourth circuit including a normal contact of the lever, the two windings of

the second motor, a seventh and an eighth asymmetric units, a reverse contact of the second switch, and a normal contact of the first switch.

2. In combination, a plurality of railway switches, a plurality of motors one for controlling each switch and each having two windings, a pair of conductors, means for reversibly supplying current to the conductors, and means controlled by the switches and including asymmetric units for at times successively connecting the two windings in series of the several motors with the conductors in such manner that current flows always in one direction through one winding of each motor. 70

3. In combination, a manually operable lever having normal and reverse positions, two railway switches each having a normal and a reverse position, two motors one for controlling each switch, means effective when the lever is moved to its reverse position to operate the first motor to reverse the first switch, means for subsequently actuating the second motor to reverse the second switch, means effective when the lever is moved to the normal position to operate the second motor to restore the second switch to its normal position, and means for subsequently actuating the first motor to restore the first switch to its normal position. 85

4. In combination, a manually operable lever having normal and reverse positions, two railway switches, two motors one for controlling each said switch, and means controlled by said lever for operating said motors successively when the lever is moved to either position to move the switches to corresponding positions. 100

5. In combination, a plurality of railway switches, a plurality of motors one for controlling each switch and each having two windings, a pair of conductors, means for reversibly supplying current to said conductors, means controlled in part by said switches for at times connecting said motors successively with said conductors, and asymmetric units connected in circuit with each motor for permitting current to flow in one direction only through one winding 110 of each said motor irrespective of the polarity of the current supplied to said conductors. 115

In testimony whereof I affix my signature.

HENRY S. YOUNG.
